BREAD BOX

Filed March 19, 1936

A 3D perspective view of a folding chair assembly. The main frame consists of a rectangular base 16 supported by legs 15. A seat 18 is hinged to the base. A backrest 17 is attached to the top of the base. A side panel 3 is attached to the right side of the base. A footrest 6 is attached to the front of the base. The backrest 17 and side panel 3 are shown in an open position. The drawing uses leader lines to point to specific parts and labels them with numbers 1 through 18 and letters A and B.

A perspective view of a rectangular frame structure. The top horizontal bar is labeled '1'. The bottom horizontal bar is labeled '3'. The left vertical bar is labeled '5'. The right vertical bar is labeled '2'. The front face of the structure is labeled '15'. A diagonal bar connecting the top-left and bottom-right vertices is labeled '17'. A diagonal bar connecting the top-right and bottom-left vertices is labeled '16'. A horizontal bar inside the frame, parallel to the bottom bar, is labeled '11'. A vertical bar on the left side of this inner bar is labeled '18'. A vertical bar on the right side of this inner bar is labeled '3'. A horizontal bar at the bottom of the inner frame is labeled '12'. A vertical bar on the left side of this bottom bar is labeled '19'. A vertical bar on the right side of this bottom bar is labeled '3'. The bottom edge of the inner frame is labeled '2'. The bottom edge of the outer frame is labeled '5'. The bottom edge of the right vertical bar is labeled '5'. The bottom edge of the left vertical bar is labeled '2'. The bottom edge of the inner frame is labeled '2'. The bottom edge of the inner frame is labeled '5'. The bottom edge of the inner frame is labeled '2'. The bottom edge of the inner frame is labeled '12'. The bottom edge of the inner frame is labeled '2'.

BREAD BOX

Fernande Leona Gamache, Burlington, Vt.

Application March 19, 1936, Serial No. 69,708

2 Claims. (Cl. 229—41)

The device forming the subject matter of this application is a box, intended primarily to contain bread but capable of being used for any other purpose. The box is a foldable structure and 5 includes foldable bottom flaps. One object of the invention is to provide novel means for stopping the downward swinging movement of the bottom flaps, so that the bottom flaps will remain within the contour of the side and end walls 10 of the box, thereby keeping the box in a rectangular shape, it being impossible for the bottom members to fold downwardly beyond a horizontal position and dump the contents of the box.

Another object of the invention is to reinforce 15 and strengthen the bottom flaps so that they will withstand wear. Another object of the invention is to provide novel flexible connections between the ends of the box and the bottom flap, the means for joining one of the flexible members 20 to one end of the box being used, also, to hold one of the side walls and the corresponding end wall together. Another object of the invention is so to construct the box that it can be folded into compact form when not in use.

25 It is within the province of the disclosure to improve generally and to enhance the utility of devices of that type to which the invention app- pertains.

With the above and other objects in view, 30 which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in perspective, a box constructed 40 in accordance with the invention, the closure being opened;

Fig. 2 is a perspective view showing the box folded and collapsed;

Fig. 3 is a transverse section of the box as it 45 appears when set up;

Fig. 4 is a section on the line 4—4 of Fig. 1;

Fig. 5 is a fragmental vertical section showing one of the bottom flaps folded upwardly and inwardly;

50 Fig. 6 is a section on the line 6—6 of Fig. 4.

In the drawing, there is shown a box B, preferably made out of cardboard, pasteboard or similar material used in the manufacture of boxes and cartons. The box B comprises oppositely-dis- 55 posed sides 1 and oppositely-disposed ends 2

hingedly and foldably connected at 3 to the sides 1. Bottom flaps 4 are hingedly and foldably connected at 5 to the sides 1.

Flexible members 6, made of canvas or other textile material are provided. The flexible members 6 are connected throughout limited areas 7 to the inner surfaces of the ends 2, adjacent to the sides 1. The flexible members 6 have free portions 8 disposed above the bottom flaps 4. As shown in Fig. 6, the flexible members 6 are ex- 10 tended between the ends 2 and the bottom mem- bers 4 and are extended upon and secured to the lower surfaces of the bottom members.

In securing the flexible members 6 to the ends 2, to form the areas 7, adhesive material may 15 be employed, and, in addition, securing devices, such as rivets 12 may be employed. The flexible members 6 are secured to the lower surfaces of the bottom flaps 4 adhesively, and also by means of securing devices, such as rivets 14. The bot- 20 tom members 4 are wide enough so that their inner portions overlap somewhat, as shown at 9 in Fig. 3.

One of the sides 1 has a tongue 11 overlapped 25 on the adjacent end 2 and secured thereto adhesively. In addition, some of the securing de- 30 vices 12 that connect one of the flexible mem- bers 6 to the corresponding end 2 also engage the tongue 11 and aid in holding it in place.

The closure for the upper end of the box B 30 may be of any desired form. For instance, it may embody top flaps 15, hingedly and foldably connected at 16 to the upper edges of the sides 1, and top flaps 17, hingedly and foldably connected at 18 to the upper edges of the ends 2. 35

When the box is set up, the end flaps 17 are folded inwardly, and the flaps 15 are folded inwardly on top of the flaps 17, the flaps 15 meet- 40 ing at their inner edges, as shown at 19 in Fig. 3. The bottom flaps 4 are swung down to approxi- 45 mately horizontal position and their inner portions overlap, as shown at 9. The flexible mem- bers 6 hold the bottom flaps 4 within the contour of the box, as shown in Fig. 6, and serve to keep the box of the rectangular form disclosed in Fig. 1. Moreover, by means of the flexible members 6, the bottom flaps 4 are prevented from folding downwardly beyond the position of Fig. 3 and dumping the contents of the box.

Because the flexible members 6 extend between 50, the ends 2 and the ends of the bottom flaps 4, as shown in Fig. 6, because the bottom flaps 4 overlap at their inner edges as shown at 9, and because the inner portions of the flexible strips 6 overlap a little, as shown in Fig. 3, the box is 55

perfectly and adequately sealed at its ends. Since the flexible members 6 extend beneath the bottom flaps 4, wear on the bottom flaps, due to shuffling the box about, is avoided, or, at least, is taken up by the textile members 6, which are better adapted to stand wear than the cardboard or pasteboard flaps 4.

In order to collapse the box into the condition of Fig. 2, the flaps 17 and 15 are folded upwardly 10 into alignment, respectively, with the ends 2 and with the sides 1. The bottom flaps 4 are folded upwardly, inside of the box, against the sides 1, as in Fig. 5. The box then is flattened down at the hinged and foldable connections shown at 15 3, and the collapsed box appears as depicted in Fig. 2.

Having thus described the invention, what is claimed is:

1. A box comprising oppositely-disposed sides 20 and oppositely-disposed ends hingedly and foldably connected to the sides, bottom flaps hingedly and foldably connected to the sides, flexible members connected throughout limited areas to the inner surfaces of the ends, adjacent to the sides,

and having free portions disposed above the bottom flaps, the flexible members being extended out of the box between the ends and the bottom members and being extended upon and secured to the lower outer surfaces of the bottom members, thereby to take the external wear imposed on the bottom members.

2. A box comprising oppositely-disposed sides and oppositely-disposed ends hingedly and foldably connected to the sides, bottom flaps hingedly and foldably connected to the sides, flexible members connected throughout limited areas to the inner surfaces of the ends, adjacent to the sides, and having free portions disposed above the bottom flaps, the flexible members being extended 15 between the ends and the bottom members and being extended upon and secured to the lower surfaces of the bottom members, one side being provided with a tongue overlapped on one end, and a securing device connecting one flexible 20 member to the corresponding end and also engaging the tongue to hold it in place.

FERNANDE LEONA GAMACHE.
